Primary Examiner — Robin V Webster

(74) Attorney, Agent, or Firm — John T. Dipre; Steven W. Miller

(57) **CLAIM**

The ornamental design for a foam cleaning implement, as shown and described.

DESCRIPTION

FIG. 1 is a top perspective view of the first embodiment of a foam cleaning implement;

FIG. 2 is a top view of the first embodiment of a foam cleaning implement shown in FIG. 1;

FIG. 3 is a right side view of the first embodiment of a foam cleaning implement shown in FIG. 1;

FIG. 4 is a left side view of the first embodiment of a foam cleaning implement shown in FIG. 1;

FIG. 5 is a front view of the first embodiment of a foam cleaning implement shown in FIG. 1;

FIG. 6 is a rear view of the first embodiment of a foam cleaning implement shown in FIG. 1; and,

FIG. 7 is a bottom view of the first embodiment of a foam cleaning implement shown in FIG. 1.

The broken line showing of the bottom portion is included for the purpose of illustrating and forms no part of the claimed design.
